UNITED STATES PATENT OFFICE.

VACLAV F. SEDLAK, OF KANSAS CITY, MISSOURI.

OIL BURNER.

Application filed December 26, 1922. Serial No. 608,858.

To all whom it may concern:

Be it known that I, VACLAV F. SEDLAK, a citizen of the United States, residing at Kansas City, in the county of Jackson and State of Missouri, have invented certain new and useful Improvements in Oil Burners; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to hydrocarbon oil burners and the primary object of the invention is to provide a novel form of oil burner so constructed that the oil will be vaporized in an efficient manner and combine with the requisite amount of air which supplies the oxygen to support combustion.

It is important in a device of this kind that the air passages admit the air in easy stream lines to reduce friction in the passage of the air through the air ports and to so arrange the air ports that there will be no counter or eddy currents within the burner because if counter or eddy currents do occur, they produce a roaring noise which obviously is objectionable.

My invention is so designed that the burner will operate without noise and the air and oil ports are so disposed that the incoming air and oil vapors will co-mingle to produce a combustible mixture of maximum efficiency.

I have also provided an oil burner of rugged construction so that it will not easily burn out and the invention contemplates the provision of means whereby liability of carbon accumulation will be reduced to a minimum because as is well understood, the more perfect the combustion, the less liability of carbon accumulation.

The invention also contemplates a burner construction in which there will be a minimum number of parts, each of which is readily accessible for inspection, the parts being simplified so that the burner can be easily assembled, and I have also provided means whereby the effective port areas may be varied to regulate the air feed although the latter feature may not, in all cases, be necessary.

The novel construction of the invention

will be clearly understood by reference to the following description in connection with the accompanying drawings, in which

Fig. 1 is a top plan view of an oil burner constructed in accordance with my invention, part of the arch being broken away to show the interior construction.

Fig. 2 is a sectional view on the line 2—2 of Fig. 1.

Fig. 3 is a top plan view of the base.

Fig. 4 is a perspective view of the arch.

Fig. 5 is a perspective view of the base, and

Fig. 6 is a bottom plan view of a slightly modified form of base.

The invention is illustrated as consisting of two main castings, a base 1 and an arch 2. The base is illustrated as triangular and near the point of each angle is an air orifice or port. The ports are designated 3, 4 and 5 and around each port is an upstanding flange 6 to support one tubular leg of the arch 2, as will be explained hereinafter.

The center of the base is provided with a concavity 7, which constitutes a priming pan for the introduction of oil to be ignited to generate sufficient heat to cause vaporization.

In the center of the base and concentric with the priming pan is an oil inlet orifice 8, having a screw threaded connection by means of which a supply pipe 9 may be secured. Surrounding the orifice is a plurality of upstanding, ring-shaped ribs 10 of progressively decreasing heights from the center toward the periphery of the base. The ring-shaped ribs are concentric with the orifice 8 and they have inclined sides to provide grooves 11 into which the oil may overflow from the orifice 8 and since each larger ring is of less height than the preceding smaller ring, it is obvious that the oil will flow from the center toward the periphery of the base and finally be received in the oil pan or concave portion 7.

The oil in the grooves as well as that in the pan can be ignited to supply the initial heat whereby the arch will be heated to a temperature sufficiently high to vaporize the oil and after the initial priming, the arch will be maintained at a temperature sufficient to cause vaporization of the oil while the burner is operating.

In order that the oil may not overflow the sides of the base I provide a flow-off port 12

in the base, which may be connected to a suitable tank or receptacle adapted to receive the overflowing oil.

Surrounding the rings 10 is a plurality of 5 arcuate lugs 13, 14 and 15, which constitute steps or base supports for corresponding lugs 16, 17 and 18, carried by the arch 2, the corresponding lugs being designed to support the central portion of the arch members 10 16, 17, and 18 serve a dual function, in that they support the central portion of the arch and also constitute flame deflectors.

The arch has three radial tubular legs 19, 20 and 21, which merge into a central chamber 23 at the center of the arch; the incoming air passing through the legs 19, 20 and 21, however, being maintained in separate stream lines by the partitions 24, 25 and 26, radially disposed from the center of the 15 arch and connected to the walls of the tubular legs so that the incoming air streams through legs 19, 20 and 21 flow through separate chambers until they finally merge into the central chamber 23 immediately above 20 the oil orifice 8.

The legs 19, 20 and 21 of the arch have shoulders 27, 28 and 29, which rest upon the upstanding flanges 6 of the respective orifices 3, 4 and 5, as will be clearly seen by reference to Fig. 2.

Between the tubular legs of the arch the arch wall is shortened to provide discharge orifices 30, 30' and 30² and at the edges of these orifices are downwardly inclined 35 flanges or lips 31, 32 and 33 to direct the flame downwardly and thereby tend to spread it over a relatively large area. Since there is a flame emitting space between each pair of legs, it will be apparent that the 40 flame will be emitted from the burner in a broad flat ring. Particularly is this true since the flame emitting spaces are elongated horizontally and since the lugs 16, 17 and 18 support the center of the arch, the 45 spaced relation between the arch and the base will be maintained even though the arch becomes heated to incandescence. Of course, it is desirable to have the arch relatively hot in order that the oil may be thoroughly 50 vaporized and when it mixes with the air, a highly inflammable combustible mixture will be provided.

I prefer to provide the orifices 3, 4 and 5 as well as the tubular legs more or less oval 55 in cross section and to so upwardly and downwardly curve the legs that the air can enter from the outside to the inside of the burner in easily bending stream lines to thereby reduce the friction of the air and 60 since the air inlet orifices through the legs are relatively large, the rate of flow of the air requisite to promote combustion can be relatively slow; therefore, there will be no liability of eddy currents being set up such 65 as would tend to cause the roaring action.

commonly present in known types of burners.

Under certain conditions it may be desirable to control the air intake ports and in order to effect the control I may provide on 70 the base 1 a plurality of radially slidable dampers, shown as plates 34, 35 and 36, mounted in guides 37-37, 38-38 and 39-39 on the base. The damper plates are connected eccentrically to a disk or plate 40 through the medium of the links 41, 42 and 43, the plates having an offset or lug 44 to which may be attached an operating rod 45 accessible from the exterior of the furnace so that the plate can be oscillated about its 80 axis to move the plates with respect to the orifices and thereby valve them. The action will be clearly apparent by reference to Fig. 6.

It will be noted that the partitions 24, 25 85 and 26, while vertical, terminate high enough above the oil inlet to provide a relatively large capacity central chamber 23 common to the three chambers formed by the legs 19, 20 and 21. This is desirable so 90 that the chamber 23 will be large enough to accommodate the incoming air from three separate legs and to do this without creating any opposing stream lines or eddy currents which tend to cause the burner to roar.

When the parts are assembled, oil is admitted through the orifice 8 by opening a valve (not shown) in pipe 9. The feed may be gravity fed or any other suitable means may be employed. The initial oil 100 will flow over the ring-shaped ribs or baffles and if enough oil is introduced, some of it will flow into the priming pan 7, where it will accumulate in a pool. This oil is then ignited and as it burns, the arch will 105 become heated. As soon as it becomes hot enough, the oil will begin to vaporize and mixing with the incoming air will provide an efficient combustible mixture. Thereafter the burning of the vapors in the 110 burner will be sufficient to maintain the arch hot enough to cause vaporization; it being understood, of course, that the arch becomes very hot in practice and as the vapors burn, they will be directed out in horizontal stream lines about the axis of the burner over a relatively wide area, the result being a burner of high efficiency which 115 will function with the minimum liability of difficulty on account of the accumulation of carbon and while I do not wish to be limited to the particular size or proportions shown, I recommend that the base and arch be rugged enough to withstand liability of cracking due to the intense heat generated and yet light enough so that an unnecessary amount of metal need not be used.

What I claim and desire to secure by Letters Patent is:

1. An oil burner comprising a base hav- 120

ing air inlet openings and a central oil inlet opening, a plurality of ring-shaped ribs concentric with the oil inlet opening, the ring-shaped ribs being of decreasing heights from the center toward the periphery of the base and forming relatively deep grooves or spaces between them, the top of the base being formed with a shallow concave portion, the surface of which will direct the flame radially, and an arch having inwardly converging, curved, tubular air conducting legs merging into a central air and vapor fuel chamber above the oil inlet in the base, the lower ends of the legs registering with the air inlet openings in the base, the lower edges of the mixing chamber having outwardly and downwardly disposed spaced flanges for directing the flame against the shallow concave portion of the base.

2. An oil burner comprising a base having air inlet openings and a central oil inlet opening, a plurality of ring-shaped ribs concentric with the oil inlet opening, the ring-shaped ribs being of decreasing heights from the center toward the periphery of the base and forming relatively deep grooves or spaces between them, the top of the base being formed with a shallow concave portion, the surface of which will direct the flame radially, an arch having inwardly converging, curved, tubular air conducting legs merging into a central air and vapor fuel chamber above the oil inlet in the base, the lower ends of the legs regis-

tering with the air inlet openings in the base, the lower edges of the mixing chamber having outwardly and downwardly disposed spaced flanges for directing the flame against the shallow concave portion of the base, and lugs depending from the central portion of the arch between the flanges, the lower ends of the lugs resting upon the base.

3. An oil burner comprising a base having a central oil inlet and air inlets near its periphery, a plurality of tubular air conducting legs resting upon the base and surrounding the air inlet openings thereof, the air conducting legs converging toward the center of the burner and merging into a central air and fuel mixing chamber above the oil inlet in the base, and lugs depending from the mixing chamber and resting upon the base to support the mixing chamber above the base to provide fuel orifices between the base and the arch.

4. An oil burner comprising a base having a central oil inlet and air inlets near its periphery, a plurality of tubular conducting legs, surrounding the air inlet openings thereof, the air conducting legs converging toward the center of the burner and merging into a central air and fuel mixing chamber above the oil inlet in the base and lugs depending from the mixing chamber in spaced relation to provide fuel orifices between the base and the arch.

In testimony whereof I affix my signature.

VACLAV F. SEDLAK.
